ATTORNEY

UNITED STATES PATENT OFFICE.

JAMES F. SHAW, OF JACKSON, MICHIGAN, ASSIGNOR OF ONE-FOURTH TO
JOSEPH M. QUIVEY, OF SAME PLACE.

BOOT.

SPECIFICATION forming part of Letters Patent No. 424,138, dated March 25, 1890.

Application filed June 26, 1889. Serial No. 315,684. (No model.)

To all whom it may concern:

Be it known that I, JAMES F. SHAW, a citizen of the United States, residing at Jackson, in the county of Jackson and State of Michigan, have invented certain new and useful Improvements in Boots, of which the following is a specification.

My invention is an improvement in felt boots; and it consists in certain novel constructions and combinations of parts, as will be hereinafter described, and pointed out in the claim.

In the drawings, Figure 1 is a side view of my improved boot. Fig. 2 is a section on about line 2 2 of Fig. 3. Fig. 3 is a section on about line 3 3 of Fig. 1, and Fig. 4 is a section on about line 4 4 of Fig. 1.

The boot comprises a foot-piece of felt or analogous material and a leg-piece of leather or analogous material; and the present invention seeks, among other improvements, to provide braces which will efficiently strengthen the boot at the points where the felt of ordinary felt boots usually cracks, and to so arrange such bracing portions that they will form the means of uniting and incasing the meeting edges of the side flaps or pieces of the felt foot-piece.

Referring to the drawings, the felt foot-piece is marked A and the leather leg-piece B. I form the foot-piece A of side pieces C, of suitable shape, having their rear edges fitting close together at the rear of the boot, and their front edges fitting close together down along the top and front of the foot-piece, the lower edges of the sections C being suitably crimped under the insole D, the outer sole E being then applied and secured by suitably stitching, as will be understood from the drawings. The leg portion of the felt foot-piece extends up well above the ankle, and the leather leg-piece fits thereon and extends in front well down toward the instep and below the bend at the top of the instep, so as to prevent cracking of the felt at such point. At the rear of the boot the leg-piece extends down over the felt to the outer sole E, and is crimped in immediately over said sole and under the crimped-in portion of the felt at the heel. This construction is especially desirable, because it not only prevents the cracking of the felt by the bending of same at the heel of the

boot, but it also prevents any damage to such felt by the strain in pulling the boot off, and permits the use of an ordinary boot-jack in removing the boot, thus rendering the removal of the boot easier and avoiding the necessity of the care now commonly required in the removal of the ordinary felt boot. The edges of the felt side pieces fit close together at the rear of the boot, immediately inside of the leather leg-piece and over the meeting edges of same. I provide a strip F, preferably of leather, which extends inside of the boot from the sole up to the top of the foot portion, and is secured by stitching along its edges through the side sections C of felt on opposite sides of the meeting edges of same and through the leg-piece. This strip F, it will be seen, forms a brace and a shield against wear of the felt at the rear inside portion of the foot-piece and receives the wear resulting from the pressure and bearing of the heel as the boot is pulled on and off the foot. This strip, being of leather, also presents a better surface than felt for the heel and facilitates the movement of the foot into and out of the boot.

Where the edges of the sections C meet at the front of the boot, I provide outside a leather strip G, which extends over the joint of sections C from the lower front portion of the leg-piece down and under the insole, and is stitched in place. Rows of stitching are also provided running down on opposite sides of the joint of sections C, and serving to secure same firmly to the bracing-strip G. It will be seen that the strip G, in addition to its use in securing the edges of sections C and lapping the joints thereof, also forms a brace, extending from the toe of the boot to the lower front end of the leg-piece, and forms a connection therebetween, thus strengthening the front part of the foot portion and reducing the liability of the felt foot-piece to crack. Within the foot-piece I provide a strip H, of canvas or other suitable material, which extends lapping the front joint of sections C from the upper to the lower edge of same, and is secured in place by stitching near its edges.

The boot so constructed is simple in make-up, firmly braced and re-enforced at the needed points, and in such manner as to give strength and also prevent the cracking of the

felt. The boot may also be easily removed from the foot by the use of a boot-jack or similar appliance without any danger of cracking or tearing the felt.

5 Having thus described my invention, what I claim as new, and desire to secure by Letters Patent, is—

10 The improved boot, substantially as herein described and shown, consisting of the felt foot-piece formed of side sections having their meeting edges arranged close together at the front and rear of the foot-piece, the leather leg-piece fitted over the leg portion of the foot-piece and having its rear portion extended down under the heel of the foot por-

tion and secured, the strip F, secured within the boot, lapping the rear meeting edges of sections, secured to such sections on opposite sides of the said meeting edge, and extended from the sole up to the top of the foot portion, 20 and the outside and inside bracing and connecting strips H and G, securing the front meeting edges of sections C, and extended from the toe-piece upward, all substantially as and for the purpose specified.

JAMES F. SHAW.
